UNITED STATES PATENT OFFICE.

GEORGE H. GERE, OF NEWARK, NEW JERSEY.

IGNITION DEVICE FOR INTERNAL-COMBUSTION ENGINES.

1,099,496.

Specification of Letters Patent.

Patented June 9, 1914.

Application filed April 16, 1913. Serial No. 761,483.

To all whom it may concern:

Be it known that I, GEORGE H. GERE, a citizen of the United States, residing at Newark, in the county of Essex and State of New Jersey, have invented certain new and useful Improvements in Ignition Devices for Internal-Combustion Engines; and I do hereby declare the following to be a full, clear, and exact description of the invention, 10 such as will enable others skilled in the art to which it appertains to make and use the same, reference being had to the accompanying drawings, and to figures of reference marked thereon, which form a part of this 15 specification.

This invention relates to ignition apparatus for internal combustion engines and more especially to the devices for making electrical contacts included in such ignition 20 apparatus.

The contact making devices, according to my invention, comprise a member which is actuated preferably from the engine crank shaft, so as to be given a continuously recurring movement in a fixed path during the 25 range of action of the piston in which the cylinder charge may be ignited when the engine is run either in forward or reverse direction, that is to say, in the two-cycle engine, in connection with which one form of my invention 30 is shown in the accompanying drawings, during a portion of the compression and power strokes. The movement of such member at other times is, of course, immaterial, as it is not called upon to perform its 35 function of making contact to close the electrical circuit, except within the range of piston movement referred to. Such member may, for example, be given a recurrent 40 movement in a fixed path during such range of piston movement, by giving it a movement of rotation, as from the engine shaft, and in such case such contact member will recurrently traverse a fixed path during its 45 entire movement, but it may be mounted and actuated in other ways so long as it travels recurrently a fixed path corresponding to the range of piston movement during which the charge is to be ignited. I may refer to 50 such contact member as the recurrently moving contact member. The remaining contact member, which is adapted to co-act with the recurrently moving contact member, is arranged adjacent to the fixed path of travel thereof above referred to. Such contact member ordinarily during the operation of

the engine is stationary relative to the recurrently moving contact member. By reason of this fact, and in order to distinguish it from the recurrently moving contact member I may refer to it generally as the local contact member. Such local contact member may be actuated in such manner as to break its contact with the recurrently moving contact member and immediately 60 thereafter to make contact therewith at a different point in the fixed path of travel of the recurrently moving member, and for this reason I shall have occasion to refer to it as alternately engaging the recurrently moving 65 contact member. The local contact member may also preferably be shifted relatively to the recurrently movable contact member to advance or retard the interval of contact and thereby the timing of the spark, and for 70 this reason I may refer to it as a shifting contact member. I may also provide means for locking the local contact member in any desired position within the range through 75 which it may be shifted to advance or retard the time of making contact, such locking means being especially useful to prevent accidental change of position where the shifting movement is performed manually.

One form of apparatus in accordance with 80 my invention is illustrated in the accompanying drawing, in which—

Figure 1 is a face view of a sparking apparatus mounted on an engine and involving one form of my invention. Fig. 2 is a 85 side view of the sparking device shown in Fig. 1. Fig. 3 is a detail illustrating the positions of the parts of the sparking apparatus when the engine is reversed, and Fig. 4 is a diagrammatic view showing one 90 form of arrangement of electrical connections for my improved sparking apparatus.

I illustrate in the drawing an engine 10 having a shaft 11 which is driven in the usual way by a piston operating in the cylinder of the engine, the piston in turn being connected to a crank on the shaft 11. This detail is not shown because it is common to internal combustion engines.

To secure an explosion in the internal 105 combustion engine, when the charge is compressed by the piston on its compression stroke, a suitable sparking device, as a spark-plug 12 (Fig. 4) is placed in a suitable position in the cylinder, the spark-plug being connected, by a wire 13, to a spark-coil 110 14, the spark-coil being connected, by the

wire 15, to the engine which forms a ground for the circuit, and a wire 16, from the plug through the battery 17 and through the switch 18, is led to the improved contact device which forms the subject-matter of this invention. The contact device is constructed to make a contact through the sparking circuit so that a spark is caused at a predetermined time to explode the mixture that has been compressed by the piston and force the piston down on its power stroke. If the spark is caused after the compression and when the piston is beginning to descend, the engine will run in one direction; I will assume it to be in the forward direction. When the engine is running well the spark, of course, may be advanced through a limited range as is usual. If, however, at any time in the rotation of the engine, the spark is caused in the mixture before the piston has sufficiently advanced upon its compression stroke to be carried over the center by its momentum, the piston is forced down before the crank has gone over the center, and the direction of the rotation of the engine is reversed. The present invention is designed to bring about the reversing of the engine by means of the sparking devices with positiveness and certainty.

The recurrently moving contact member is designated by the numeral 19. Such contact member is shown as mounted in the circular insulation disk 20, and such disk may be of any preferred insulating material as porcelain, fiber, or the like. The disk 20 and the contact member 19 borne thereby may be directly connected to the engine shaft 11 and may rotate therewith. The contact member 19 is grounded as by being brought into contact with the shaft 11.

The local contact member 25 is mounted upon a support by which it is supported adjacent to the recurrently moving contact member 19, and such support may comprise a ring 21 mounted on the engine boss 38 concentric with the shaft 11. The local contact member 25, as shown, comprises two separated contact points 26 and 27 and is carried by the ring 21 in such manner as to be insulated therefrom. In the form shown, the ring 21 is provided with an upward extension 22 to which is secured a plate or strip of insulating material 23, upon which the contact member 25, preferably constructed in the form of a yoke, as shown, is pivotally mounted substantially mid-way between the contact points 26 and 27. The insulating plate 23 carries the plate 24 which in turn carries the means for turning or swinging the contact member 25 upon its pivot and for locking the same in place, and in the form shown, such turning and locking means comprise the link 28 pivotally secured to the contact member 25 at one side of the pivotal mounting thereof, and containing an insulating portion 29, said link being connected, at its opposite end, to a handle 30 which is pivoted to the plate 24 at 31. Projecting from the boss 32 of the handle 30 is a nose 33 which engages a head 34 on a rod 35, the rod 35 sliding in the bearing 36, and the head 34 of said rod being projected away from said bearing 36 by means of a spring 37. It will be seen that when the handle 30 is operated, the head 34 is pressed down, and when the nose 33 passes over its center, the head assists in completing the movement of the handle and also locks the handle 30 and the local contact member 25 in adjusted position and against accidental shifting or rocking. The local contact member 25 thus alternately engages the recurrently moving contact 19 at different points when it is rocked upon its pivot by means of the handle 30, causing a quick change of the place of contact between it and the recurrently moving contact 19 by bringing its contact point 27 into co-acting relation with the recurrently moving contact 19 in place of the contact point 26, or vice versa. It will thus be seen that when the extension 22 of the ring 21 is vertical and the disk 20 is so arranged on the shaft 11 that the engagement between the contacts takes place, for instance, as in Fig. 1, the contact member 19 has moved approximately thirty degrees from the vertical in the direction of the arrow *a*, the arrow indicating the forward direction of rotation of the shaft 11. I will assume that when this contact takes place the piston has completed its compression stroke and has been carried over by the fly-wheel so that it is a short distance on its power stroke, that is, if the contact 19 has moved thirty degrees from the vertical, and the piston was at the limit of its compression stroke when the contact 19 was vertical, the piston has traveled on its power stroke substantially one-sixth of its distance of travel when the contact is made and the spark and the resulting explosion occurs. It will thus be readily understood that so long as the engine moves in the direction of arrow *a*, the recurring contact and explosion keeps the engine running, the point 26 makes contact with the contact 19 and the direction of rotation of the engine continues forward.

If it is desired to reverse the engine, the handle 30 is manipulated to move the local contact member 25 on its pivot so that the contact point 26 is lifted and the contact point 27 is forced down in contact with the disk as shown in full lines in Fig. 3. It is assumed that when this takes place the engine is running in the direction of arrow *a*. The contact point 27 now comes into engagement with the recurrently moving contact member 19 a substantial distance before the piston has completed its compression stroke, the explosion takes place and the engine is

instantly reversed and driven back in the direction of arrow *b*. It will thus be seen that by this rocking of the local contact member 25 on its pivot, the direction of rotation of the engine can be positively and certainly reversed.

I prefer to make the whole support for the local contact movable, so as to be able to advance and retard the time of making contact. For this purpose I may mount the ring 21 so that it can be swung, concentric to the shaft 11, on the boss 38 of the machine, and I may provide shifting and locking means, constructed, for example, as follows: The ring 21 is split to form the projecting ends 39. A rod 40 with a flange 41 is arranged to extend through the ends 39, the lower end 39 being screw-threaded and receiving the screw-threaded end 42 of the rod 40. The rod 40 extends up through a bearing 43 mounted on the plate 24 and is provided with the hand-wheel 44. When the hand-wheel is turned to unscrew the screw 42, the ring 21 is released at its ends sufficiently to allow the whole support to be swung, and when it is properly adjusted, the wheel 44 may again be turned to tighten up the ends 39 and the ring 21 is bound around the boss 38. This adjustment provides for shifting the local contact for advancing and retarding the spark, and it will be seen that the spark can be advanced or retarded when the engine is running either forward or backward. The dotted lines in Fig. 3 show the local contact member in the position it occupies when the spark is retarded and the engine is reversed. The range through which the local contact member 25 may be brought into contact with the recurrently moving contact member 19 in practice, when the member 25 is placed normally vertically above the engine shaft as illustrated, extends from the position where such retarded spark contact is made, as indicated in dotted lines in Fig. 3, to a corresponding position on the other side of the vertical, and it is this portion of the path of the contact traversed by the contact 19 during which effective electrical contact is made and which must be a fixed path and be traversed recurrently by the contact 19. So long as the contact 19 travels such fixed path recurrently, its movement elsewhere is immaterial and it may traverse any path in other parts of its movement. Such fixed path as shown is the arc of a circle, but it may have any other desired form and the local contact may be shifted in any manner which will keep it adjacent to such fixed path and in position to make contact with the contact 19 traversing the same.

In the type of ignition device illustrated herein, the shifting support for the local contact member is arranged vertically when the engine is to be started either forward or

backward so that when the handle 30 is up or down the contact made by the contact point on the local contact member 25 in engagement is the same distance on either side from the vertical point or top center of the disk 20. The support should also be placed in a vertical position before the direction of rotation of the engine is to be reversed. This is desirable, as it is easy to determine substantially the vertical position of the support and such arrangement does away with guess work as to slowing up the engine to the proper speed for reversing, since the shifting of the support to a vertical position retards the spark and automatically slows the engine down to the proper number of revolutions at which the reversing operation should take place.

It will be evident that multiple cylinder engines can be equipped with this ignition device by the simple expedient of providing the proper number of contact devices connected for sparking each cylinder in proper sequence, and by a similar construction of handle the multiple local contacts can be actuated to engage the multiple recurrently moving contacts.

It will be understood that other constructions can be employed within the scope of my claims, and that other arrangements of circuit than those illustrated may be resorted to for bringing about the operations and functions enumerated herein without departing from the scope of my invention.

Having thus described my invention, what I claim is:—

1. An ignition apparatus for internal combustion engines comprising in combination a recurrently moving contact member arranged to pass recurrently along a fixed path of travel, and a local contact member mounted adjacent to said path of travel and adapted to engage the moving contact member at separated points and to be out of engagement therewith at intermediate points in said fixed path of travel.

2. In an engine sparking circuit, a recurrently moving contact, a support shiftable along the path traversed by the recurrently moving contact, a contact member on said support and provided with separated contact making portions, and means for moving the last named contact member on its support so as to bring the contact making portions thereof alternately into engagement with said recurrently moving contact.

3. The combination of an engine and its sparking circuit, with a contact device in the circuit, the contact device consisting of a revolving contact operated from the engine, a yoke supported adjacent to the revolving contact, and means for swinging the yoke to cause its ends to alternately engage the revolving contact.

4. The combination of an engine and its
sparking circuit, with a contact device in
the circuit, the contact device consisting of
a revolving contact operated from the en-
gine, a yoke supported adjacent to the re-
volving contact, means for swinging the
yoke to cause its ends to alternately engage
the revolving contact, and means for lock-
ing the yoke in its alternate positions.

10 5. The combination of an engine and its
sparking circuit, with a contact device in
said circuit, the contact device consisting of
a recurrently moving contact operated from
the engine, a shifting contact to engage the
15 moving contact, the shifting contact being
disposed so that it engages the moving con-
tact after the piston of the engine has com-
pleted its compression stroke, and means
for actuating the shifting contact so that
20 it engages the moving contact before the
completion of the compression stroke.

6. An ignition device for internal com-
bustion engines comprising a rotary contact
operated from the engine, a support, a yoke
25 mounted on the support and adapted to
swing so that its ends can be alternately
brought in contact with the revolving con-
tact, means for shifting and locking the
yoke in its alternate positions, and a han-
30 dle on the shifting and locking means for
its manipulation.

7. An ignition device for internal com-
bustion engines comprising a rotary contact
operated from the engine, a support, a yoke
35 mounted on the support and adapted to
swing so that its ends can be alternately
brought in contact with the revolving con-

tact, means for shifting and locking the
yoke in its alternate positions, a handle on
the shifting and locking means for its ma-
nipulation, and means for adjusting and se-
curing the support in different positions.

8. An ignition device for internal com-
bustion engines comprising a non-conduct-
ing disk operated from the engine shaft, a
45 contact in the disk, a support adjacent to
the disk, a yoke swinging on the support
with its ends adapted to alternately engage
the disk and its contact, the disk being
adapted to limit the movement of the yoke
50 when it swings, means for locking the yoke
in its alternate positions, and means for
swinging the yoke.

9. An ignition device for internal com-
bustion engines comprising a non-conduct-
ing disk operated from the engine shaft,
a contact in the disk, a support adjacent to
the disk, a yoke swinging on the support
55 with its ends adapted to alternately engage
the disk and its contact, the disk being
adapted to limit the movement of the yoke
when it swings, means for locking the yoke
in its alternate positions, means for swing-
ing the yoke, the support being mounted to
swing concentrically in its relation to the
60 disk, and means for locking the support in
different positions.

In testimony, that I claim the foregoing,
I have hereunto set my hand this 14th day
of April, 1913.

GEORGE H. GERE.
